 tion of Massachusetts

Application July 22, 1950, Serial No. 175,452

7 Claims. (Cl. 51—118)

1

The invention relates to lapping machines, and more particularly to a machine for automatically lapping the opposite faces of successive flat workpieces to a predetermined size and finish.

One object of the invention is to provide a simple and thoroughly practical lapping machine automatically to lap the opposite plane faces of successive workpieces to a predetermined size and finish. Another object is to provide a lapping machine having two opposed rotatable lapping wheels and a work cage therebetween for conveying successive flat workpieces in a circular eccentric path between said wheels to simultaneously lap the opposed surfaces thereof to the required extent during a single pass through the machine. Another object is to provide an annular rotatable ring gear for supporting and driving the work cage about an axis eccentric to the axes of the lapping wheels. Another object is to provide a motor driven mechanism positively to rotate the ring gear and cage at a slow controlled rate to govern the duration of the lapping operation. A further object is to provide automatic loading and discharge mechanisms automatically to load and discharge successive workpieces from the continuously rotating work cage before and after lapping. Another object of the invention is to provide a plurality of anti-friction rollers to locate and support the ring gear in a predetermined plane normal to its axis of rotation and also to provide a rotary support therefor. It is a further object of the invention to provide an axial adjustment for one and/or both of the lapping wheels to facilitate compensation for wear and for truing of the lapping wheels. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a fragmentary plan view of the lapping machine with the upper lapping wheel and its supporting and driving mechanism removed;

Fig. 2 is a staggered sectional view, taken approximately on the line 2—2 of Fig. 1;

Fig. 3 is a vertical sectional view, through the lapping machine, with the work cage mechanism removed;

Fig. 4 is a fragmentary plan view, on an en-

2

larged scale, taken approximately on the line 4—4 of Fig. 2, showing one of the three roller supports for the work cage driving gear;

Fig. 5 is a fragmentary sectional view, on an enlarged scale, taken approximately on the line 5—5 of Fig. 4, through one of the adjusting screws;

Fig. 6 is a fragmentary sectional view, on an enlarged scale, taken approximately on the line 6—6 of Fig. 2, through the bracket for supporting one set of the guide rollers for the cage driving gear;

Fig. 7 is a plan view of the parts shown in Fig. 5;

Fig. 8 is a fragmentary sectional view, taken approximately on the line 8—8 of Fig. 7;

Fig. 9 is a fragmentary sectional view, on an enlarged scale, taken approximately on the line 9—9 of Fig. 1, showing one of the driving connections between the work cage and its driving gear;

Fig. 10 is a fragmentary front elevation, taken approximately on the line 10—10 of Fig. 1, of the work loading mechanism;

Fig. 11 is a cross-sectional view, on an enlarged scale, taken approximately on the line 11—11 of Fig. 10;

Fig. 12 is a vertical sectional view, taken approximately on the line 12—12 of Fig. 2, through the adjustable support for the lower lapping wheel;

Fig. 13 is a fragmentary plan view, on an enlarged scale, showing the adjustably mounted loading and discharge platen;

Fig. 14 is a sectional view, taken approximately on the line 14—14 of Fig. 13;

Fig. 15 is a fragmentary cross-sectional view, through one of the workpieces;

Fig. 16 is a fragmentary front elevation, on an enlarged scale, of a portion of the work loading mechanism;

Fig. 17 is a plan view of the parts shown in Fig. 16;

Fig. 18 is an electrical diagram showing the electrical control mechanism for the work cage driving and work loading mechanisms.

Referring more particularly to the embodiment illustrated, the lapping machine may be constructed in its general aspects similar to the lapping machine illustrated in my prior U. S. Patent No. 2,103,984, dated December 28, 1937. This machine, as illustrated, may comprise a base 10 which rotatably supports a lower lapping wheel 11. The base 10 is provided with an upwardly extending column 12 having an outwardly ex-

tending horizontal portion 13 which rotatably supports a vertical spindle 14. The spindle 14 is provided at its lower end with a supporting plate 15 which carries a rotatable lapping wheel 16.

Power may be obtained from any suitable source, such as an overhead drive shaft or an electric motor mounted on the machine. For the sake of illustration, a belt drive has been shown comprising a driving belt 20 which serves to rotate a pulley 21. The inner portion of the pulley is formed as one part of a cone clutch. A slidably mounted clutch member 22 serves to cooperate to permit power to be readily connected or disconnected. The pulley 21 is rotatably supported on a horizontally extending shaft 23 which is supported in bearings 24, 25, 26 and 27 in the base 10. The clutch member 22 is slidably keyed to the shaft 23. When the clutch is in full line position as indicated in Fig. 3, no power is transmitted to the shaft 23. When it is desired to rotate the shaft 23, the cone clutch member 22 is moved toward the right (Fig. 3) into engagement with the cone clutch member within the pulley 21 so as to cause a rotation of the shaft 23. In order that the clutch may be readily operated from the front of the machine, a pivotally mounted control lever 28 is supported on a stud 29 on the base 10. The lower end of the lever 28 is connected by a pin 30 with a link 31 which is connected by means of a rod 32 supported in bearings 33 and 34 with a yoked member 35 and engages a groove 36 in the hub 37 of the clutch member 22. By movement of the control lever 28 in a counterclockwise direction, the clutch member 22 may be thrown into engagement with the clutch member within the pulley 21 to cause rotation of the shaft 23. A spring pressed roller 38 cooperating with an arrow point 39 on the yoked member 35 serves to hold the clutch either in or out of engagement.

The shaft 23 is provided with a worm 45 which meshes with a worm gear 46 mounted on the lower end of a vertical shaft 47. The shaft 47 is connected by a universal joint 48 with a shaft 49. The shaft 49 is preferably a telescopic shaft and is connected by a universal joint 50 with a vertical shaft 51 supported in bearings 52 and 53 in a bracket 54 mounted on the top of the column 12. The shaft 51 is provided with a pulley 55 which is connected by belts 56 with a pulley 57 which is mounted on a rotatable sleeve 58. The sleeve 58 is slidably keyed by keys 59 to an upwardly extending projection 60 of the spindle 14, so that when the clutch 22 is engaged, the vertical spindle 14 supporting the upper lapping wheel 16 will be rotated.

The bracket 54 is adjustably mounted on the upper surface of the column 12 and is provided with a screw adjustment comprising a screw 62 which is rotatably supported in a bracket 63 fixed to the column 12 and is screw threaded into the bracket 54 so that the bracket 54 may be adjusted transversely of the machine to obtain the desired drive tension on the belts 56.

The lower lapping wheel 11 is mounted on a rotatable spider 65 which is supported on the upper end of a vertical shaft 66. The lower end of the shaft 66 is provided with a worm gear 67 which meshes with a worm 68 mounted on the shaft 23. It will be readily apparent from the foregoing disclosure that rotary motion of the shaft 23 will be imparted through the driving mechanisms above described to impart a rotary motion to the upper lapping wheel 16 and the

lower lapping wheel 11 to rotate the lapping wheels in the opposite directions.

A suitable counter-balance mechanism is provided to counter-balance the weight of the upper lapping wheel 16 and its supporting mechanism. This mechanism is not considered a part of the present invention and consequently has not been illustrated in detail. This mechanism is identical with that shown and fully described in my prior U. S. Patent No. 2,103,984, dated December 28, 1937, to which reference may be had for details of disclosure not contained herein.

In order to limit the downward movement of the upper lapping wheel 16, a suitable stop mechanism is provided to positively limit the downward movement of the lapping wheel so that it bears a definite and predetermined relationship with the lower lapping wheel and the work. This stop may comprise an adjustable stop 75 which is adjustably mounted in a bracket 76 which is supported in fixed relationship with the column 12. The stop 75 is provided with a screw threaded portion meshing with a correspondingly threaded aperture within the bracket 76. A transversely extending clamping screw 78 is mounted within the bracket 76 and serves to clamp the stop 75 in adjusted position. A movable stop screw 80 is supported in a bracket 81 adjustably fixed to an axially movable sleeve 72 which supports the spindle 14. The sleeve 72 is provided with a plurality of spaced threaded holes 82 so that the bracket 81 may be clamped in various positions on the sleeve 72 by means of screws. The stop screw 80 passes through a threaded aperture in the bracket 81 and is provided at its upper end with a graduated micrometer adjusting member 86 which enables a fine adjustment of the stop screw 80 to vary the lower position of the upper lapping wheel 16 as desired. In order that the stop screw 80 may be locked in adjusted position, the bracket 81 is preferably provided with a slot which extends from the end of the bracket to the threaded aperture. A clamping screw 88 extends transversely through the bracket 81 at a point intermediate the slotted area and serves to bind the bracket 81 when it is desired to lock the stop screw 80 in a predetermined adjusted position. By means of a plurality of threaded holes 82 in the sleeve 72, a quick adjustment of the bracket 81 may be obtained to adjust the stop in setting up the machine for lapping work-pieces of varying thicknesses.

A suitable adjusting mechanism is provided for adjusting the position of the lower lapping wheel 11 so as to maintain its operative face in the same plane. After normal wear of the lapping wheel or after truing operations, it is desirable to raise the lower lapping wheel 11 so as to reposition the plane of the operative face thereof. This is preferably accomplished by mounting the lower lapping wheel 11 on a plate 90 which is in turn supported on a cup-shaped housing 91 having an internal thread 92 which meshes with or engages an external threaded portion 93 of a cup-shaped member 94 which is fixedly mounted on the spider 65. It will be readily apparent from the foregoing disclosure that by a rotary adjustment of the cup-shaped member 91, the lower lapping wheel 11 may be raised or lowered as desired. In order to facilitate rotary adjustment of the cup-shaped member 91, a plurality of holes 95 are provided in the member 91 which may be engaged by a special spanner type wrench to facilitate adjustment thereof. In order to lock the member 91 in adjusted position,

a plurality of cylindrically shaped locking members 96, 96a and 96b fit within cylindrically shaped apertures in the member 91 and are provided with inner threaded portions 98 which mesh with or engage the external threaded surface 93 of the cup-shaped member 94. A clamping screw 99 is provided for each of the clamping members 96 by means of which the members 96 may be moved longitudinally to lock the member 91 in adjusted position on the member 94.

In order to automatically lap a plurality of successive workpieces to the desired and predetermined extent, a work cage is provided comprising a disc-shaped work cage 100 having a plurality of work receiving apertures 101. The work cage 100 is preferably supported by an annular ring gear 102. The ring gear 102 is provided with a recess 103 to receive the work cage 100. In order to drive the work cage 100 with the gear 102, a plurality of driving pins 104, 104a and 104b are fixedly mounted on the ring gear 102. The pins 104 are arranged to engage radial slots 105, 105a and 105b formed in the periphery of the work cage 100.

The ring gear 102 and the work cage 100 are preferably supported to rotate about an axis eccentric relative to the axes of the upper lapping wheel 16 and the lower lapping wheel 11 so that, as shown in Fig. 1, the workpiece engages the throat between the upper lapping wheel 16 and the lower lapping wheel 11 and travels in a circular path eccentric to the axes of the lapping wheels so that the workpieces travel from an entering point where they engage the lapping wheels at their peripheries and pass across the entire face of the lapping wheel so that at a midway point the workpieces move so that they engage the inner portions of the lapping wheels after which they again continue in a circular path to the outer peripheries thereof. Due to the opposite rotation of the lapping wheels and also due to the path of movement of the workpiece across the plane faces of the two wheels, the workpieces are caused to rotate within the apertures 101 so as to produce the desired relative motion to lap the opposite surfaces thereof to a predetermined size and finish.

A suitable supporting and driving mechanism is provided for supporting the ring gear 102 and the cage 100 in a predetermined plane. The base 10 serves as a support for a pan 110 (Fig. 2) which serves as a support for a pair of vertically arranged rods 111 and 112 (Fig. 1) which serve as supports for brackets 113 and 114 respectively. The rods 111 and 112 are adjustably mounted on the pan 110. The rods pass through a cylindrical aperture 115 in brackets 116 and 117 which are adjustably fastened to the pan 110 by means of screws 118, 119, 120 and 121. The brackets 116 and 117 are slotted and provided with clamping screws 122 to facilitate clamping the rods 111 and 112 in adjusted position. The bracket 113 is provided with a pair of rollers 125 and 126 which engage the inner peripheral surface of the ring gear 102 to form an anti-friction support therefor. The bracket 113 is also provided with a roller 127 which engages the under-surface of the ring gear 102 to form a support therefor. Similarly the bracket 114 is provided with a pair of rollers 128 and 129 which are arranged to engage the inner peripheral surface of the ring gear 102. The bracket 114 is also provided with a roller 130 which engages and supports the under-side of the ring gear 102. The pan 110 is also provided with a bracket 135 (Fig. 2) which

is similarly provided with a pair of rollers 136 and 137 which engage the inner peripheral surface of the ring gear 102. The bracket 135 also supports a pair of rollers 138 and 139 which engage the under-side of the ring gear 102 and which cooperate with the rollers previously described to support and determine the path of rotation of the ring gear 102 which rotates about an axis eccentric to the axes of the lapping wheels 16 and 11. The bracket 135 is adjustable in a transverse direction to facilitate adjustment of the position of the rollers in setting up the machine. The bracket 135 is provided with a pair of elongated slots 140 and 141 (Fig. 4). Clamping screws 142 and 143 pass through the elongated slots 140 and 141 respectively and are screw threaded into a bracket 144 which is adjustably mounted on the outer peripheral surface of the pan 110 by means of screws 145 and 146. By adjustment of the position of the brackets 113 and 114 and 135, the position of the guiding rollers 125, 126, 128, 129, 136 and 137 may be varied to determine the position of the path of rotary movement of the ring gear 102. By a vertical adjustment of the brackets 113, 114 and 135, the rollers 127, 130, 138 and 139 may be adjusted to determine the plane of rotation of the ring gear 102 and the cage 100.

Each of the adjusting screws 118, 119, 120, 121, 145 and 146 are provided with a push and pull adjustment as illustrated in Fig. 5. The clamping screw 146 is screw threaded into the pan 110. The screw 146 passes through a central aperture 147 in a threaded sleeve 148. The sleeve 148 is screw threaded into the bracket 144. The right-hand end of the threaded sleeve 148 bears against a plane surface on the pan 110. The lock nut 149 is provided for locking the threaded sleeve 148 in adjusted position. It will be readily apparent from the foregoing disclosure that by loosening the screw 146 the threaded sleeve 148 may be adjusted in either direction to move the bracket 144 either toward or from the outer peripheral surface of the pan 110 after which the clamping screw 146 may be again tightened and the lock nut 149 locked.

A driving mechanism is provided for rotating the ring gear 102 and the work cage 100 at a relatively slow speed to produce the desired lapping action. This mechanism may comprise an electric motor 160 having an integral speed reduction unit 161 fixedly attached thereto. This motor driven gear reduction unit may be any of the standard well known mechanisms such as are now available. The motor speed reduction unit is mounted on the bracket 144 which as previously explained is adjustably mounted on the pan 110. The speed reduction unit 161 is provided with a driven shaft 162 having a gear 163 which meshes with a gear 164 mounted on a rotatable shaft 165. The shaft 165 is provided with a gear 166 which meshes with the ring gear 102. It will be readily apparent from the foregoing disclosure that rotary motion of the motor 160 and the speed reduction unit 161 will be imparted to rotate the ring gear 102 and the cage 100 at a relatively slow speed. If different speeds are desired, the gears 163 and 164 may be changed to provide either an increased or a decreased speed of the ring gear 102.

It is desirable to provide an automatically operated work loading mechanism for automatically conveying successive workpieces to the holes or pockets 101 in the work cage 100. The particular workpiece illustrated in drawings has been illustrated in Fig. 15. This workpiece is in the

form of a washer 168 having a central hole 169. An upwardly extending flange 170 projects from the upper face of the washer 168. A recess 171 is provided in the lower face of the washer. The lapping machine is arranged to lap the relatively small area upper face 172 and the larger area lower face 173 (Fig. 15). This mechanism may be a hopper type feeding mechanism such as for example that manufactured by the Detroit Power Screwdriver Company of Detroit, Michigan, and disclosed in U. S. Patent No. 2,350,486 to R. W. Bailey, dated June 6, 1944, to which reference may be had for details of disclosure not contained herein. This work feeding mechanism may comprise a rotatable hopper 175 which is driven by an electric motor 176 through a worm and worm gear unit contained within the casing 177. This assembly is mounted on a bracket 178 which is in turn adjustably mounted on a vertically extending rod 179. The rod 179 is adjustably clamped in a bracket 180 which is fastened to the bracket 144. The bracket 144 as above described is adjustably mounted on the outer periphery of the pan 110. Clamping screws 181 and 182 serve to clamp the rod 179 in the desired position. Clamping screws 183 and 184 are provided on the bracket 178 to facilitate clamping the bracket 178 in the desired adjusted position on the rod 179. The rotary hopper wheel serves to pick up washers 168 to be lapped in an inverted position as illustrated in Fig. 15 and to pass the washers through a loading chute 185 which turns the washers 168 into an upright position for loading into apertures 101 of the cage 100. The loading chute 185 is provided with a T-shaped clearance slot 186 through which the workpieces slide onto the upper surface of the work cage 100. After leaving the chute 185, the workpieces pass through a box-like chute 187 having a plurality of adjustably mounted flat springs 188, 189 and 190 which serve to hold the workpieces downwardly and to retard the movement of the workpieces until they drop into the holes 101 in the work cage 100. The tension of the springs 188, 189 and 190 may be adjusted by means of set screws 191, 192 and 193 respectively. A guide plate 202 is mounted on one side of the chute 187 to facilitate guiding the workpieces 168 into the path of the apertures 101 in the work cage 100.

A suitable safety device is provided to stop the rotation of the ring gear 182 and the work cage 100 and also to stop the work loader 175 in case the washers are not in proper position and in case they do not fall into the holes 101 in the cage 100. This mechanism may comprise a lever 194 which is pivotally mounted on studs 195 carried by a bracket 196. The normal position of the lever 194 is determined by the setting of a stop screw 197 which is supported by an arm 198 carried by the bracket 196. If the workpieces 168 fail to drop into the holes 101 in the work cage 100, the protruding workpieces will engage the under-surface of the lever 194 and rock the lever 194 in a counter-clockwise direction (Fig. 16) about pivot studs 195. The other end of the lever 194 is provided with a set screw 199 which is arranged to engage the actuating plunger 200 of a normally closed limit switch 201. Rocking movement of the lever 194 in a counter-clockwise direction will serve in case the workpieces 168 are not properly located within the cage apertures 101 to open the limit switch 201 and thereby to stop the rotation of the motor 160, thereby stopping the rotary motion of the ring gear 182 and

the work cage 100 to prevent damage to the machine by improperly positioned workpieces.

The automatic work loader 175 is arranged to pick up workpieces and to position them in the proper position in the chute 185 so that the flanged portion 170 will be upward when the workpiece is placed in the apertures 101 of the work cage 100.

As shown in Figs. 1, 13 and 14, workpieces 168 are loaded into the apertures 101 of the cage 100 at a point outside the periphery of the lapping wheels 16 and 11. It is therefore desirable to provide an arcuate shaped loading platform 205 adjacent to the periphery of the lower lapping wheel 11 having an upper surface which lies in the same plane with the operative face of the lapping wheel 11. The loading platform 205 is provided with a downwardly extending integral bracket 206 which is fastened by two pairs of adjusting screws 207 and 208 to the pan 110. The adjusting screws 207 and 208 are identical with that shown in Fig. 4 and comprise means whereby the bracket 206 may be adjusted in a vertical plane to align the upper operative surface of the loading platform 205 in a horizontal plane.

In setting up the machine, the lower lapping wheel 11 may be adjusted vertically so that its upper or operative surface lies in the same plane with the loading platform 205. It will be readily apparent from the foregoing disclosure that workpieces loaded into the apertures 101 of the cage 100 are carried along the operative face of the loading platform 205 into engagement with the throat formed between the upper lapping wheel 16 and the lower lapping wheel 11. As shown in Fig. 1 rotation of the cage 100 at a slow rate of speed causes the workpieces to travel in a circular path eccentric to the axes of the lapping wheels 16 and 11, so that the workpieces travel from the outer peripheral surfaces of the lapping wheels 16 and 11 to the inner surfaces thereof after which they again travel across the faces of the wheels to the outer peripheries thereof. At this point the finished lapped workpieces ride onto and are supported by the loading platform 205. When the lapped workpieces successively reach an aperture 209 formed in the loading platform 205, they drop through the loading platform 205 onto an inclined surface 210 and onto an inclined chute 211 into a container 212. It will be readily apparent from the foregoing disclosure that workpieces automatically loaded by the motor driven work loader 175 are automatically fed to the apertures 101 of the cage 100 after which the workpieces make one circular path through the throat between the lapping wheels 16 and 11 during which time the upper and lower faces of the workpiece 168 are lapped to the desired and predetermined extent. After one complete pass between the wheels, the workpieces 168 are automatically discharged from the cage 100 and slide downwardly into a receiving container 212 (Figs. 13 and 14).

During the passage of the workpieces between the grinding wheels, due to the oppositely rotating lapping wheels and the eccentric circular path through which the workpieces travel, a rotary motion is imparted to the workpieces relative to the lapping wheels so that a desired and predetermined lapping operation is simultaneously performed on the opposite faces thereof. In lapping the type of workpiece such as shown in Fig. 15, a relatively large area on the lower surface is lapped whereas a relatively small area on the upper surface is simultaneously lapped.

If desired, lapping wheels of varying grit size or grade may be utilized to offset the differences in areas to be lapped so that a desired and uniform lapping operation is obtained on both surfaces.

Referring now to Fig. 18, an electrical diagram has been illustrated to show the operation of the safety device in connection with the work loader. Electric power is supplied through the power lines L1, L2 and L3. A main switch 215 is provided for connecting power with a magnetic switch 216 for controlling the work cage driving motor 160 and the work loader driving motor 176. A low voltage current is provided for the control circuit. A transformer 217 has its primary circuit connected with the power lines L1 and L3. The secondary circuit thereof is connected through a starter switch 218 to close a circuit so as to energize the magnetic starter switch 216 so as to start the motors 160 and 176. A holding circuit serves to maintain the magnetic starter switch 216 closed. A stop switch 219 is provided whereby the circuit may be broken to deenergize the magnetic starter switch 216 when desired to stop the cage driving motor 160 and the work loader driving motor 176. The normally closed limit switch 201 is connected in the control circuit so that if and when the limit switch 201 is opened in case workpieces do not properly locate in the work cage, the opening of the limit switch 201 will serve to deenergize the magnetic starter switch 216 thereby stopping the cage driving motor 160 and the work loader driving motor 176.

The operation of this improved lapping machine will be readily apparent from the foregoing disclosure. Assuming all of the adjustments to have been previously made and the operative faces of the lapping wheels trued to parallel plane surfaces, a plurality of workpieces are placed within the automatic motor driven work loader 175. The workpieces are automatically fed by the loader 175 into the chute 185 into engagement with the apertures 101 of the work cage 100. Due to the relatively slow rotary motion of the cage 100 and its driving gear 102, the workpieces are successively carried in a single circular eccentric path through a lapping throat formed between the lapping wheels 16 and 11 to lap the opposed surfaces thereof to a predetermined size and finish. After one complete pass between the wheels the workpieces are then automatically discharged into the receiving container 212.

If either of the lapping wheels become worn away or require truing, a truing operation is performed in the conventional manner by means of a truing mechanism such as that shown in my prior U. S. Patent No. 2,082,736, dated June 1, 1937 to which reference may be had for details of disclosure not contained herein. After truing of either or both of the wheels, it is then necessary to readjust the stop 80 for the upper lapping wheel 16 to allow the lapping wheel to resume a normal operating position relative to the work cage 100. It is also necessary to vertically adjust the lower lapping wheel 11 in a manner above described to reposition the operative face thereof in a plane coinciding with the plane of the loading platform 205. It will be readily appreciated from the foregoing disclosure that the cage 100 and its supporting gear 102 is never changed or adjusted after the initial setup but the lapping wheels are adjusted to compensate for wear or truing.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a lapping machine having a base, a pair of vertical axially aligned rotatable spindles on said base, a pair of rotatable lapping annuli each having a plane operative face mounted on the adjacent ends of said spindles, means including a slidably mounted sleeve on said base rotatably to support one of said spindles, means including an adjustable stop on said sleeve to facilitate maintaining said lapping faces a predetermined distance from each other during the entire lapping operation, a work support including an annular gear surrounding the lower lapping annulus, a work cage having a plurality of work receiving apertures supported by said annular gear and positioned between the opposite faces of said annuli, means including a plurality of symmetrically arranged rollers on said base rotatably to support said annular gear, said rollers being arranged so that the gear and cage rotate about an axis off-set relative to the axes of said annuli, and means including a motor driven gear reduction driving mechanism on said base having a driven gear meshing with said annular gear so as to rotate the cage at a slow speed to carry work pieces between the lapping annuli in a circular path eccentric to the lapping annuli.
2. In a lapping machine as claimed in claim 1, 40 in combination with the parts and features therein specified of an automatically operated work loading apparatus supported on said base, a chute connected with said loading apparatus to convey workpieces from said apparatus to apertures in the work cage, a motor on said base to drive said loading apparatus, guiding means supported by the base to guide workpieces from said chute into alignment with the apertures in said cage, a limit switch supported in fixed relation 45 with said chute which is operatively connected to stop both the cage driving and the loading apparatus motors when closed, and a trip finger pivotally supported on said chute in a position to be actuated by workpieces failing to drop into the cage apertures to actuate said switch so as to stop both the work loader motor and the cage driving motor.
3. In a lapping machine as claimed in claim 1, 60 in combination with the parts and features therein specified of an automatically operated motor driven work loading apparatus, a work chute between the loading apparatus and cage to convey workpieces from said apparatus to apertures in the work cage, guiding means on said base to guide workpieces from said chute into alignment with the cage apertures, a plurality of spring fingers supported by said guiding means with said guiding means to facilitate locating successive workpieces in cage apertures, a limit switch on said chute which is operatively connected to stop both the cage driving and the loading motors when closed, and a trip finger pivotally mounted adjacent to the discharge end of said chute in a position to be actuated by work- 65 pieces failing to drop into the cage apertures to
5. In a lapping machine as claimed in claim 1, 70 in combination with the parts and features therein specified of an automatically operated motor driven work loading apparatus, a work chute between the loading apparatus and cage to convey workpieces from said apparatus to apertures in the work cage, guiding means on said base to guide workpieces from said chute into alignment with the cage apertures, a plurality of spring fingers supported by said guiding means with said guiding means to facilitate locating successive workpieces in cage apertures, a limit switch on said chute which is operatively connected to stop both the cage driving and the loading motors when closed, and a trip finger pivotally mounted adjacent to the discharge end of said chute in a position to be actuated by work- 75 pieces failing to drop into the cage apertures to

stop both the work loader motor and the cage driving motor.

4. In a lapping machine having a base, a pair of vertical axially aligned spindles on said base, a pair of rotatable lapping annuli each having plane operative faces mounted on the adjacent ends of said spindles, means on said base to rotate said spindles in opposite directions, a work support comprising a relatively large ring gear rotatably supported relative to the base, a cage receiving aperture on said ring gear, a work cage supported in said aperture having a plurality of spaced work receiving apertures, means including driving lugs on said gear to rotate said cage, said cage and ring gear being arranged to rotate about an axis off-set relative to the axes of the lapping annuli, means including a motor driven mechanism to rotate said ring gear at a slow speed, the work apertures being arranged to pass successive workpieces in an arcuate path between the operative faces of said annuli so that the workpieces travel from the outer periphery to the inner peripheries of said annuli and then travel to the outer peripheries thereof, an automatically actuated motor driven work loading mechanism including a chute on said base to convey successive workpieces to said cage apertures, and means including a discharge chute on said base to discharge lapped workpieces from said cage after one pass through the machine.

5. In a lapping machine having a base, a pair of oppositely rotating lapping annuli each having plane operative faces, a pair of vertical axially aligned spindles on said base to support said annuli, means including a slidably mounted sleeve on said base rotatably to support one of said spindles, means including an adjustable stop on said sleeve to maintain said faces a predetermined distance from each other, a work support including a rotatable annular ring gear, a cage receiving recess therein, a rotatable cage in said recess having a plurality of work receiving apertures which is supported and driven by said ring gear, an anti-friction support including a plurality of symmetrically arranged rollers for said ring gear to support the cage to rotate in a horizontal fixed plane about an axis off-set relative to said spindles, means including a motor driven driving mechanism on said base to rotate said ring gear and cage at a slow speed to carry successive workpieces to be lapped in a circular path between said annuli eccentric to the lapping annuli, and means independently to adjust both of said lapping annuli axially to maintain their operative faces in predetermined planes relative to said cage during a lapping operation.

6. In a lapping machine, as claimed in claim 5,

in combination with the parts and features therein specified in which the anti-friction support for the work cage comprises a plurality of symmetrically arranged rollers in engagement with a plane face on the ring gear to support the cage and to determine its plane of rotation, and a plurality of symmetrically arranged rollers in engagement with a cylindrical face on said ring gear to determine the axis of rotation of the work cage.

7. In a lapping machine having a base, a pair of vertical axially aligned spindles on said base, a pair of opposed rotatable lapping annuli each having a plane operative face mounted on adjacent ends of said spindles, means including a slidably mounted sleeve on said base rotatably to support one of said spindles, means including an adjustable stop on said sleeve to facilitate maintaining said lapping faces a predetermined distance from each other during a lapping operation, a work support including a rotatable cage between the operative faces of said lapping annuli having a plurality of work receiving apertures, means including an annular gear rotatably supported on said base, a cage receiving recess on said annular gear to support said cage for rotation in a fixed plane about an axis off-set relative to the axes of said spindles, means including a motor driven gear reduction unit on said base operatively connected to rotate said cage at a slow speed to carry successive work pieces to be lapped in a circular path between said annuli so that the work pieces pass from the outer peripheries to the inner peripheries and to the outer peripheries thereof during a single pass therethrough, and means including a nut and screw adjusting mechanism interposed between the other spindle and lapping annulus to adjust the latter annulus relative to the base to compensate for wear so as to maintain the lapping face in a predetermined plane relative to the case.

HERBERT S. INDGE.
